United States Patent Office

Des. 181,907
Patented Jan. 14, 1958

181,907

SUBSOIL CULTIVATOR

Kenneth E. Goit, Minneapolis, Minn.

Application July 20, 1955, Serial No. 37,050

Term of patent 7 years

(Cl. D39—1)

Fig. 1 is a rear elevational view of a subsoil cultivator showing my new design;

Fig. 2 is a top plan view; and

Fig. 3 is a side elevational view.

The dominant features of my design reside in the portions shown in full lines.

I claim:

The ornamental design for a subsoil cultivator, as shown and described.
